UNITED STATES PATENT OFFICE

2,440,126

CARRIAGE HOOD CONSTRUCTION

Robert E. Strott, East Templeton, Mass., assignor
to Thayer Company, Gardner, Mass., a corpora-
tion of Massachusetts

Application September 28, 1945, Serial No. 619,075

2 Claims. (Cl. 296—137)

1

This invention relates to new and improved constructions in carriage hoods, particularly for infants' carriages.

Objects of the invention include the provision of a "seamless" hood; i. e., exteriorly seamless as to the front hood bow, and obviating the necessity for the conventional seam in the hood extending across the same to form a pocket for said bow, this conventional seam being difficult to guide and therefore often crooked and ill-appearing; the provision of said "seamless" hood for both lined and underlined, or padded or unpadded hoods; the provision of a single line of stitching appearing only at the junction of the hood and its visor, said single line of stitching connecting the exterior material of the hood to the visor and finishing a pocket for the bow at the same time, the pocket comprising a fold in the exterior hood material in the case of the unlined hood, and a fold in the lining material in the case of the lined hood, said line of stitching thereby providing a securement pocket for the bow and appearing at the exterior of the hood as the conventional stitching for the visor, leaving the hood free of stitching and seams.

Other objects and advantages of the invention will appear hereinafter.

Reference is to be had to the accompanying drawings, in which

Fig. 1 is a general view of a hood for a carriage;

Fig. 2 is a section thru the hood, visor, and front bow of an unlined hood;

Fig. 3 is a section thru the hood, visor, and front bow of a lined hood; and

Fig. 4 is a fragmentary view of the top of the visor from the front.

Fig. 1 shows a carriage 10 having a folding hood 12 extended and folded by a conventional break connection 14. The hood in the drawing is illustrated as having a front bow 16 and four other bows at 18, and for the purposes of this application, the front bow may be taken as U-shaped with the free ends of the arms of the U pivoted at 20. The hood also has a visor 22.

As shown in Fig. 2, the hood 12 extends to the left and slightly upwardly at 24 forming a bead, thence downwardly, under and around the front bow 16, terminating in a free end 26 tucked into the bead 24, as shown.

The visor has an end 28 tucked down in front of the bow, and a line of stitching 30 passes thru the visor end 28, interiorly thereof, thru the bead 24 and the end 26 binding all together completing a holding pocket for the bow 16. Another line of stitching 32 thru the bead and end 26 may also be used to stiffen the bead if desired.

The drawings exaggerate the bead 24 for clarity of illustration, and it is pointed out that this bead actually appears as a narrow length of piping. In any case, no other stitching is required to form the pocket for the bow, but the hood is smooth

and stretched taut by reason of the bow pressing upwardly and forwardly on the hood due to the connection 14.

Fig. 3 illustrates the invention as applied to a lined hood, and in this case the hood 12 is folded under at 34, resting on the end of the visor material at 36. The lining is represented at 38 and it extends forwardly under the bow 16, is folded over on itself at 40, and then passes up and over the bow as at 42, terminating in an end 44 sewed to the lining only interiorly of the hood, to finish the bow pocket. A single line of stitching 46 serves to connect the hood, the lining and the visor. In this case, also, the drawing is somewhat exaggerated and actually the stitching squeezes the hood material to again make it appear like thin piping.

Both forms of the invention provide a "seamless" hood of good appearance and without unnecessary stitching heretofore thought to be required to hold the bow.

Divisional application Serial Number 692,187, filed August 22, 1946, covers the subject matter disclosed in Fig. 2.

Having thus described my invention and the advantages thereof, I do not wish to be limited to the details herein disclosed, otherwise than as set forth in the claims, but what I claim is:

1. A carriage hood, a bow therefor, a lining, the latter being generally co-extensive with the hood and folded over on itself to contain the bow, stitching securing the hood to the lining at the fold of the latter, said stitching being located wholly to one side of the bow, and means connecting the lining to itself adjacent the edge of the bow opposite the fold, said means being located wholly at the other side of the bow, the latter being wholly contained in a pocket formed by the lining and the hood being free of the bow.

2. A carriage hood, a bow therefor, a lining folded over the bow at the front edge of the hood, the folded over portion of the lining lying concealed between the hood and lining and being secured to the lining, stitching securing the lining and hood at said front edge of the hood, and a visor having an edge lying between the hood and folded over lining, the stitching passing through the visor to secure the same.

ROBERT E. STROTT.
